United States Patent Office

Des. 178,922
Patented Oct. 9, 1956

178,922

CAMERA

Allan B. Johnson, Encino, and Frederick G. Mackay,
Anaheim, Calif., assignors to Sawyer's Inc., Progress,
Oreg., a corporation of Oregon

Application February 24, 1956, Serial No. 40,311

Term of patent 14 years

(Cl. D61—1)

FIG.1

FIG. 2

FIG. 3

FIG.4

FIG.5

FIG.6

Fig. 1 is a front elevational view of a camera embodying our new design;

Fig. 2 is a top plan view thereof;

Fig. 3 is a side elevational view thereof;

Fig. 4 is a rear elevational view thereof;

Fig. 5 is a bottom plan view thereof; and

Fig. 6 is a side elevational view of the side opposite that shown in Fig. 3.

We claim:

The ornamental design for a camera, as shown.
